UNITED STATES PATENT OFFICE

2,592,076

VISE WITH ANTITILTING MEANS FOR THE
MOVABLE JAW

Viktor Spinnler, Basel, Switzerland

Application December 23, 1947, Serial No. 793,370
In Denmark February 8, 1947

2 Claims. (Cl. 81—26)

1

The present invention relates to a vise with one fixed and one movable jaw, the latter being arranged on a slide rail, which is displaceable in a guide in the fixed jaw and can be firmly clamped by tipping, the movable jaw being displaceable on the slide rail by means of an eccentric lever in order to press it against a workpiece.

The vise according to the invention is distinguished from known vises of the kind in that the counter-bearings of the slide rail, which take the counter-pressure of the movable jaw and of the slide rail, are formed by adjusting screws arranged in the guide of the fixed jaw, hardened and each fitted with a counter-nut, and that the guide rail consists of unhardened iron.

The arrangement of hardened counter-bearings in connection with slide rails consisting of soft iron, makes possible instantaneous and certain tipping or clamping of the slide rail to the counter-bearings, which is not always the case in known vises. Since the set screws serving as counter-bearings are glass-hard, they are practically not subject to any wear. The set screws are conveniently accessible from outside and can be easily regulated, so that the clamping jaws may be adjusted exactly to each other at any time. If the slide rail should in the course of time become worn through severe stressing, it can easily be taken out and overhauled, i. e. flattened at the surfaces which cooperate with the set screws. By a simple readjustment of the set screws the jaws may be again easily regulated, whereupon the vise is practically again as good as new.

One form of embodiment of the object of the invention is illustrated by way of example in the drawing, in which:

Fig. 1 shows a side view of the vise mounted on a work bench, with some parts in section,

Fig. 2 a top view of Fig. 1,

Fig. 3 a section taken on the line 3—3 in Fig. 1,

Fig. 4 a section taken on the line 4—4 in Fig. 1,

Figs. 5 and 6 show elevation and plan views, respectively, of an adjusting screw.

The illustrated vise has a fixed jaw 1 and a movable jaw 2. The fixed jaw 1 is fitted with a circular foot plate 3, from the underside of which projects a centrally located vertical pivot pin 4, the pin 4 and base 3 being relatively immovable. The pivot pin 4 is provided with a threaded extension 5 and with a square collar 6. The fixed jaw 1 is supported with its foot plate 3 on a square plate 7 which is attached by means of screws 8 to the work bench 9 and has a central square hole 10. The pivot pin 4 passes

2

through this square hole, the square collar 6 fitting into the square hole 10, thus preventing the foot plate 3 of the jaw 1 from rotating with respect to the square plate 7. A fixing nut 11, provided with a lever 12, is screwed on to the threaded extension 5 of the pivot pin 4. By tightening this fixing nut, engagement of the square collar 6 with the square hole 10 is maintained. When the fixing nut is loosened and the vise is lifted, the square collar 6 can be raised out of the square hole 10, the vise turned through 90° and again clamped in the new position in the manner described above.

Above the foot plate 3 the fixed jaw 1 has a guide 13 of rectangular cross-section, in which a slide rail 14 is guided so that it can be displaced longitudinally. The slide rail 14 consists of two pieces of flat iron, parallel to each other, arranged at a distance from each other and connected together by three cross pieces or webs 15. The cross pieces 15 are connected to one of the pieces of flat iron by welding and to the other piece of flat iron by a screw connection 16. The counter-pressure acting on the movable jaw 2 when clamping a workpiece, is taken on the one hand by two hardened set screws 17 lying below the spaced flat irons of the rail 14 and on the other hand by two set screws 19 horizontally offset with respect to the screws 17. This counter-pressure constitutes a moment about the bottom of the slide rail 14, which moment is counter-balanced by a moment comprised by the upward thrust on the set screws 19 by the axial distance between the pairs of set screws 17 and 19. The set screws 19 are positioned above the spaced flat irons and are also hardened. The set screws 17 and 19 can be individually locked in vertically adjusted position by lock-nuts 18 and 20, respectively. Play for regulating the horizontal setting of the slide rails is provided by making the vertical inside dimension of the guide 13 greater than the depth of the rail 14. A stop in the form of a rib 21 is arranged on the inner surface of the guide 13. This stop limits clockwise movement of the slide rail 14 and wobbling of the latter, yet permits the slide to be tilted upwardly a slight amount so that the movable jaw and slide can be easily shifted by hand either toward or away from the fixed jaw.

At the front end of the slide rail 14 the movable jaw 2 is guided for limited sliding movement by means of a close-fitting guide 22. A leaf spring 24 is fixed by means of a bolt 25 to a lug 23, which is attached to the underside of said guide. The leaf spring is positioned between

3

the flat irons of the slide rail 14 and bears against the front cross piece 15 in such a way that it biases the movable jaw away from the fixed jaw 1 and against an eccentric 26, which is pivotally supported between the front end of the irons. The axle 27 of the eccentric is supported in suitable holes drilled in the flat-iron ends, and is secured by nuts 28 screwed on to the ends of the axle projecting beyond the flat irons. The eccentric 26 situated on the axle 27 between the flat irons has a stop piece 29 for limiting the position of the eccentric when loose, and has a lever 30 for operating the eccentric.

For clamping any desired workpiece the clamping lever 30 is taken hold of by one hand and the slide rail is pulled out far enough to allow the workpiece to be easily inserted between the jaws 1, 2. Then the distance between the jaws is diminished by pushing the slide rail in until the jaws come to rest against the workpiece, after which, by swivelling the clamping lever 30 downwards, the workpiece is clamped fast, in doing which the slide rails 14 are clamped between the pairs of set screws 17 and 19, and are, through the friction thus produced by the clamping pressure against the screws 17, 19, held fast, and so secured against axial displacement.

As can be seen from Figs. 5 and 6, one end of each set screw is provided with an axial recess 17a which contacts the slide rail. The outer diameter of this recess is somewhat smaller than the core diameter of the screw, so that an annular shoulder 17b is formed. This annular shoulder represents only a comparatively small surface, so that when the clamping lever 30 is operated, a large specific pressure is exerted by the slide rails 14 on the annular surfaces 17b to ensure immediate frictional connection between the set screws and the slide rail.

What I claim is:

1. In a vise, a guide having an elongated aperture therethrough, a fixed jaw on said guide, a slide movably mounted in the elongated aperture in said guide, a movable jaw slidably mounted on said slide in opposed relationship to the fixed jaw, a lever pivoted on said slide, an eccentric formed on the lever and in operative engagement with the movable jaw, and anti-tilting means comprised by at least two set screws positioned in alignment transversely of the aperture in the guide and extending upwardly through the bottom of the latter adjacent the end facing

5

the movable jaw and contacting the bottom of the slide, at least two other set screws also positioned in alignment transversely of the aperture in the guide, said other set screws extending downwardly through the top of the guide and being horizontally displaced from the first set screws in a direction away from the movable jaw, and contacting the top of the slide, whereby tilting movement of said slide and movable jaw away from the fixed jaw is prevented during work

10

clamping movement of said lever, and a transversely positioned guide rib formed on the bottom of the aperture and guide adjacent the end which is opposite the end facing the movable jaw so as to limit a reverse tilting movement when said movable jaw and slide are being manually shifted either toward or away from the fixed jaw.

15

2. In a vise as defined in and by claim 1, and said slide being comprised in part by a pair of spaced apart parallel rails movable through the aperture in the guide, said first mentioned set screws constituting a pair of set screws in transverse alignment with respect to the axis of the aperture in the guide extending upwardly through the bottom of the latter and respectively contacting the bottom of the rails of the slide, and said second mentioned screws constituting a pair of transversely aligned set screws extending downwardly through the top of the guide, horizontally displaced from the first pair of set screws and respectively contacting the top of the rails of the slide.

20

25

30

35

4

the movable jaw and contacting the bottom of the slide, at least two other set screws also positioned in alignment transversely of the aperture in the guide, said other set screws extending downwardly through the top of the guide and being horizontally displaced from the first set screws in a direction away from the movable jaw, and contacting the top of the slide, whereby tilting movement of said slide and movable jaw away from the fixed jaw is prevented during work

10

clamping movement of said lever, and a transversely positioned guide rib formed on the bottom of the aperture and guide adjacent the end which is opposite the end facing the movable jaw so as to limit a reverse tilting movement when said movable jaw and slide are being manually shifted either toward or away from the fixed jaw.

15

2. In a vise as defined in and by claim 1, and said slide being comprised in part by a pair of spaced apart parallel rails movable through the aperture in the guide, said first mentioned set screws constituting a pair of set screws in transverse alignment with respect to the axis of the aperture in the guide extending upwardly through the bottom of the latter and respectively contacting the bottom of the rails of the slide, and said second mentioned screws constituting a pair of transversely aligned set screws extending downwardly through the top of the guide, horizontally displaced from the first pair of set screws and respectively contacting the top of the rails of the slide.
